CLAIM

The ornamental design for a twisted handle for a hair tool,
as shown and described.

DESCRIPTION

FIG. 1 is a front perspective view of a twisted handle for a
hair tool in accordance with the invention;

FIG. 2 is a top view thereof;

FIG. 3 is a front view thereof;

FIG. 4 is an end view of the twisted handle for a hair tool
as seen from the left side of FIG. 3;

FIG. 5 is a rear view thereof;

FIG. 6 is an end view of the twisted handle for a hair tool as
seen from the right side of FIG. 3; and,

FIG. 7 is a bottom view thereof.

The broken lines in the drawings showing portions of a hair
tool are for illustrative purposes only. The straight vertical
broken line at the proximal end of the twisted handle for a
hair tool in FIGS. 2, 3, 5 and 7 defines the boundary of the
claimed design. None of the broken lines form a part of the
claimed design.
